DESIGN FOR A FRAME FOR A TANTALUS SET

Andrew Cravaritis, New York, N. Y., assignor to
National Silver Deposit Ware Co., Inc., New
York, N. Y., a corporation of New York

Application December 10, 1937, Serial No. 73,512

Term of patent 7 years

To all whom it may concern:

Be it known that I, Andrew Cravaritis, a citizen of the United States, residing at New York city, county of Bronx, State of New York, have invented a new, original, and ornamental Design for a Frame for a Tantalus Set, of which the following is a specification, reference being had to the accompanying drawing, forming part thereof.

Figure 1 is a front elevational view of a frame for a tantalus set, showing my new design;

Figure 2 is an end view of the frame;

Figure 3 is a top view of the frame.

I claim:

The ornamental design for a frame for a tantalus set, substantially as shown.

ANDREW CRAVARITIS.
